EXTENSION TABLE

Irving Segal, New York, N. Y.

Application June 15, 1945, Serial No. 599,633

5 Claims. (Cl. 311—55)

1

This invention relates to extension tables and the same has particular reference to an improved table of said character having a top rigidly affixed to the frame thereof and a shiftable leaf adapted to be projected to an extended position at one side of the top and to be retracted from said extended relation to an out-of-the-way position beneath the top.

The invention has in view the provision of means for mounting the leaf for guided shifting movement to dispose the same in either retracted or extended position and for supporting the same upon the frame in said extended relation.

The invention further comprehends a pair of slide bars secured to the under side of the leaf and angularly disposed with reference to the longitudinal sides of the frame and having angular sliding movement with reference thereto for shifting said leaf to a position forwardly of and offset laterally with reference to the top and said bars being guidedly mounted in notches in the end of the frame and being recessed for bearing engagement upon the upper edge of the frame adjacent said notches for supporting the leaf thereon in longitudinal alignment with the top.

The invention further includes means carried by said bars adapted to be adjusted for varying the height of the leaf when in extended position in order that the same may be disposed with the upper surface thereof flush with the upper surface of the top.

With the foregoing and other objects in view reference is now made to the following specification and accompanying drawings in which is illustrated the preferred embodiment thereof.

In the drawings:

Fig. 1 is a top plan view of a table constructed in accordance with the invention and illustrating the leaves in extended position and the top partly broken away to show the underlying parts.

Fig. 2 is a view in elevation thereof with one of the leaves shown in extended position and the other in retracted position and with the legs partly broken away.

Fig. 3 is a view in end elevation thereof.

Fig. 4 is a cross-sectional view taken approximately on line 4—4 of Fig. 1.

Fig. 5 is an enlarged fragmentary sectional view taken on line 5—5 of Fig. 1 with the right hand leaf shown in elevated supported position.

Fig. 6 is a fragmentary perspective view illustrating one of the leaves in offset extended position.

Fig. 7 is a fragmentary vertical sectional view taken approximately on line 7—7 of Fig. 1 with

2

the slide bars shown in supported position upon the table frame.

The invention is illustrated in the drawings in its application to a table provided with an auxiliary leaf at each end thereof although it is to be understood that the same is not so limited and may include an extensible leaf at each or either end thereof. The table includes a rectangular top 10 rigidly affixed to a supporting structure consisting of a frame 11 and legs 12 secured to the frame at the corners thereof. The frame 11 includes oppositely disposed longitudinally extending side panels 13 which are cut away at their opposite ends providing an elevated central portion to which the top 10 is secured and defining recesses 14 located beneath the top 10 and extending inwardly at the opposite ends of the frame for receiving therein auxiliary leaves 15 to dispose the same in an out-of-the-way retracted position supported upon the upper edges defined by the recesses 14 and arranged with the outer edges of the leaves substantially flush with the edges of the top. The frame 11 also includes opposite end panels 16 having their upper edges spaced from the top 10 and disposed flush with the upper edges defined by the recesses 14 in the longitudinally extending panels 13. The panels 16 are provided with notches 17 and 18 in their upper edges which are spaced unequal distances from the ends of the panels respectively, the notch 17 being located at a lesser distance from the adjacent end of the panel than the notch 18.

In order to provide means for supporting the leaves 15 for sliding movement to dispose the same in either extended position at one side of the top or in a retracted position within the recesses 14 beneath the top, a pair of spaced slide bars 19 are provided for each leaf which are secured to the under side thereof by fastening elements 20 and extend through the notches 17 and 18 respectively at an angle to the longitudinal sides of the frame 11. The bars 19 are slidable in the said notches and have their inner ends slidably arranged in guides formed by laterally spaced blocks 21 secured to the under side of the top and bridged by transversely extending strips 22 secured to the lower edges thereof. The bars 19 are cut away in their bottom edges adjacent their inner ends thereby providing longitudinally extending portions 23 of lesser height which portions have sliding engagement in the said guides, the extreme ends of the bars being provided with stops 24 for limiting the outward movement thereof.

The bars 19 of the leaves are adapted to seat upon the upper edges of the panels 16 respec-

tively of the frame 11 at one side of the notches 17 and 18 for supporting the leaves in longitudinal alignment with the top 10. For this purpose the bars are each right angularly recessed in cross-section which recesses are formed in their bottom edges and side faces as at 25. The medial portions of said recesses are provided with depending adjusting screws 26 which are secured in the upper faces thereof with the free ends of said screws disposed so as to seat upon the upper edges of the panels 16 to thereby support the leaf thereon in extended longitudinal alignment with the top.

The bars 19 are also longitudinally recessed in their upper edges as at 27 so as to permit of the elevation of the leaves when shifting the same from the offset position shown in Fig. 6 to the position shown in Fig. 7 in which the bars 19 are supported upon the upper edge of the panel 16.

In order to shift one of the leaves 15 from its out-of-the-way position under the top 10, the same is pulled outwardly thereby effecting a sliding of the bars 19 in the said guides and in the notches 17 and 18 to thereby dispose the leaf in offset extended position as shown in Fig. 6. The leaf is then elevated thereby raising the upper portion of the bars 19 above the top of the panel 16 whereupon the leaf is then shifted laterally into longitudinal alignment with the top so that the shoulders defined by the recesses 25 are disposed above the upper edge of the panel 16 adjacent the notches 17 and 18 respectively. The leaf is then lowered until the adjusting screws 26 engage the upper edge of the panel 16 adjacent the said notches thus supporting the leaf in longitudinal alignment with the top and with the upper surface and side edges of the leaf flush with the upper surface and side edges of the top.

It will be understood that the adjusting screws 26 may be regulated so as to vary the height of the leaf when the same is disposed in extended position in order that the leaf will be flush with the upper surface of the top 10 when the leaf is supported in extended position.

The lower edges of the reduced portions 23 of the slide bars 19 are each inclined towards the stop 24 thereof as illustrated in Fig. 5 to thereby provide a cam edge adapted to engage with the strip 22 to force the bar against the under side of the top 10 when the leaf is disposed in extended aligned position. The upper edges of the bars are each provided with a recess 27 above the arcuate recess 25 to permit of the elevation of the leaf when shifting the same from the offset position shown in Fig. 6 to the position shown in Fig. 7 with the bars supported on the panel 16.

What is claimed is:

1. In an extension table, a supporting frame, a table top rigidly affixed to said supporting frame, an auxiliary leaf movable from a position beneath the top to an extended position at one side thereof, a pair of spaced slide bars secured at their outer ends to the under side of said leaf and extending beneath the table top diagonally with reference to the longitudinal edges thereof, said supporting frame having a pair of notches in the upper edge thereof and means secured to the under side of said table top in which said bars are longitudinally slideable to dispose the leaf in extended relation with the ends thereof offset out of alignment with opposite edges of the table top and said bars having shoulders extending inwardly in corresponding side faces

thereof adapted to seat upon the upper edge of the supporting frame at one side of said notches for supporting the leaf upon said frame in longitudinal alignment with the top.

2. In an extension table, a supporting frame, a table top rigidly affixed to said supporting frame, an auxiliary leaf movable from a position beneath the top to an extended position at one side thereof, a pair of spaced slide bars secured at their outer ends to the under side of said leaf and extending beneath the table top diagonally with reference to the longitudinal edges thereof, said top and supporting frame having guides in which the bars are longitudinally slideable in angular relation to the edges of the top to thereby dispose the leaf in extended relation with the ends thereof offset out of alignment with opposite edges of the table top and said bars being recessed in corresponding side faces thereof defining shoulders adapted to overlie and seat upon the upper edge of the frame adjacent said guides therein for supporting the leaf upon said frame in longitudinal alignment with the top.

3. In an extension table, a supporting frame, a table top rigidly affixed to said supporting frame, an auxiliary leaf movable from a position beneath the top to an extended position at one side thereof, a pair of spaced slide bars secured at their outer ends to the under side of said leaf and extending beneath the table top diagonally with reference to the longitudinal edges thereof, said supporting frame having a pair of notches in the upper edge thereof and means secured to the under side of said top defining guides in which notches and guides said bars are longitudinally slideable in angular relation to the edges of the top to thereby dispose the leaf in extended relation with the ends thereof offset out of alignment with opposite edges of the table top, said bars being formed with recesses in corresponding side faces thereof which open through the bottom edges of the bars and have horizontal upper faces adapted to be disposed in overlying relation with the upper edge of the frame adjacent said notches when the leaf is elevated and shifted laterally from said offset relation to a position in longitudinal alignment with the top and means secured to the upper faces of said recesses adapted to seat upon the upper edge of the frame for supporting the leaf upon the frame in longitudinal alignment with the top and said means being adjustable for varying the height of the leaf to thereby dispose the upper surface thereof flush with the upper surface of the top.

4. In an extension table, a supporting frame, a table top rigidly affixed to said supporting frame, an auxiliary leaf movable from a position beneath the top to an extended position at one side thereof, a pair of spaced slide bars secured at their outer ends to the under side of said leaf and extending beneath the table top diagonally with reference to the longitudinal edges thereof, said top and supporting frame having guides in which the bars are longitudinally slideable in angular relation to the edges of the top to thereby dispose the leaf in extended relation with the ends thereof offset out of alignment with opposite edges of the table top and said bars being provided with shoulders extending inwardly in corresponding side faces thereof adapted to overlie and seat upon the upper edge of the frame adjacent said guides therein for supporting the leaf upon said frame in longitudinal alignment with the top.

5. In an extension table, a supporting frame, a table top rigidly affixed to said supporting frame,

an auxiliary leaf movable from a position beneath the top to an extended position at one side thereof, a pair of spaced slide bars secured at their outer ends to the under side of said leaf and extending beneath the table top diagonally with reference to the longitudinal edges thereof, said top and supporting frame having guides in which the bars are longitudinally slidable in angular relation to the edges of the top to thereby shift the leaf from a position under the top to an extended position at one end thereof with the ends of the leaf offset out of alignment with opposite edges of the table top, said bars being recessed in corresponding side faces thereof, adjustable means secured to the upper walls of said recesses respectively and said leaf being shifted laterally from said offset relation to dispose said adjustable means upon the upper edge of said frame adja-

cent said guides therein with the leaf disposed in alignment with the top and said adjustable means being adjustable for varying the height of the leaf to thereby dispose the upper surface of the leaf flush with the upper surface of the top.
